Re. 16,161

UNITED STATES PATENT OFFICE.

RANDAL E. TALLEY, OF NORTH IRWIN, PENNSYLVANIA.

COMPOSITE GEAR WHEEL.

Original No. 1,492,145, dated April 29, 1924, Serial No. 609,632, filed December 29, 1922. Application for reissue filed March 20, 1925. Serial No. 17,106.

To all whom it may concern:

Be it known that I, RANDAL E. TALLEY, a citizen of the United States, residing at North Irwin, in the county of Westmoreland and State of Pennsylvania, have invented 5 certain new and useful Improvements in Composite Gear Wheels; and I do hereby declare the following to be a full, clear, and exact description of the invention, such as 10 will enable others skilled in the art to which it appertains to make and use the same.

My invention relates to composite articles, such as the articles of manufacture embodying the well-known phenolic condensation 15 products, more especially to composite gear wheels having a central metallic support or hub portion and a non-metallic working rim portion mounted thereon.

It is among the objects of my invention 20 to provide a composite gear-wheel structure which shall be relatively noiseless in operation, which shall be of durable and strong mechanical qualities, and which shall operate smoothly and efficiently for the transmission of high-speed rotary movement and relatively large loads when associated with various machine elements.

It is a further object of this invention to 25 provide a gear-wheel of the above-designated character which shall be of simple and relatively inexpensive construction and which shall be adapted to manufacture in production quantities.

There have been in use various types of 30 non-metallic gears which are constructed of composite material, such as glued layers of raw hide, vulcanized fiber, compressed oil impregnated fibers, or fibrous material compounded with a consolidating agent or binder. These composite materials have been 35 utilized in various types of composite gear-wheel structures inasmuch as they require reinforcing or supporting elements to adapt them to the severe operating conditions to 40 which gear wheels are subjected. All of these gear wheels serve their purpose within the limits of their physical and mechanical characteristics and they rank in their order of importance respectively as listed.

The fiber gear is characterized by its 45 dense, hard structure which lends to it a brittleness that is detrimental to the function of a gear wheel as it commonly results in failure of the teeth when subjected to 50 shock and impact. Fiber deteriorates rapid-

ly if subjected to moisture or oil. The raw-hide gear is yielding and spongy, which limits its usefulness of the compressive strength of the material, and, further, raw hide is 60 pervious to moisture and atmospheric changes which distorts the gear teeth due to warping, swelling and shrinking.

The compressed cotton or fabric gear comprises a spun, or spinnable textile fabric or 65 loose fibers which are assembled between a pair of steel plates by which the material is compressed to provide a working body portion and the plates are secured as by rivets or screws to sustain the load on the gear teeth. The compressed gear is of necessity shrouded to the outer extremity of the 70 gear teeth as the plates are the sustaining body portion which resists the loads applied to the teeth and prevents their disintegration.

The consolidated compressed fabric gear 75 wheel is not supported by plates and constitutes a self-sustaining body portion which is formed by consolidating the fabric under 80 heat and pressure with a hardened binder such as the well-known phenolic condensation products. The consolidated body portion has excellent wearing qualities and the 85 teeth formed therein are mechanically strong and durable and resist the erosion of the tooth surface effected by rolling contact with the metallic tooth surface of the mating gear. However, such a gear wheel, because 90 of its density, produces sound which, although of a relatively low pitch, is nevertheless irritable, especially when employed in the timing gear train of automobile engines for which they are commonly used. Another disadvantage of the consolidated 95 gear is its relatively high density throughout, which sometimes causes splitting due to the difference in the thermal expansion of the composite rim and its metallic supporting hub upon which it is molded.

My present invention is directed to a 100 gear-wheel structure which embodies the desirable characteristics of the compressed fabric and the consolidated fabric gear wheels without possessing any of the detrimental qualities of either.

I propose to form the working body portion in which the gear teeth are formed into a consolidated and relatively hard mass while leaving its contiguous body portion 105 a relatively soft mass of lower density. I 110

further propose to mount such a composite rim upon a metallic center or hub which may comprise various forms and which may employ various mechanical means for securing the rim thereon. A gear wheel so constructed provides a durable wearing surface and a resilient tooth portion. The toothed rim functions as an isolated unit and is free to move axially on the hub limited by the untreated support. The yielding support serves as a connection between the toothed body portion and the metallic center or hub.

In the accompanying drawings, constituting a part hereof, and in which like reference characters designate like parts,

Figure 1 is a cross-sectional view of a composite gear wheel embodying the principles of my invention;

Fig. 2 is an exploded view, partially in cross-section, of a compressed rim showing an intermediate step of the manufacturing process in which the rim is assembled to the hub by means of a pair of pressure dies 20 provided with suitable welding electrodes;

Fig. 3 is a cross-sectional view of an assembled gear wheel having hub members secured to the rim by welding;

Fig. 4 is an elevational view of an assembled gear wheel made in accordance with my invention;

Figs. 5, 6 and 7 are respectively cross-sectional views of fragmentary portions of composite gear wheels illustrating modified forms of mounting of the rim portion to the hub, and various ways of securing the hub body portions;

Fig. 8 is a perspective view of a fragmentary portion of a strip of fibrous sheet material employed in forming the rims of the gear wheels; and

Fig. 9 is a plan view of a segment cut from fibrous sheet material which may be utilized in my gear-wheel structure.

Referring to Fig. 1, the gear wheel therein illustrated comprises a hub portion 1 and a non-metallic rim portion 2, provided with a toothed periphery 3. The hub member 1 consists of a pair of flanged discs 4, which are formed in a suitable manner to provide the seating hub portions 5, flanges 6 and a web 7. The hub 5 is provided with an opening 8, by which it is adapted to be mounted on a shaft or other rotatable element.

The non-metallic rim 2 may be formed in various ways, as by punching suitable segments (Fig. 9) or rings from fibrous sheet material, such as paper, fabric and the like, and the outer body portion 9 (Fig. 9) of such segments or discs are treated with a binding agent, such as the well-known phenolic condensation products. The treated segments or rings are assembled in superposed layers and consolidated under heat

and pressure to form a unitary ring having a dense, consolidated outer body portion 10 and an untreated contiguous dove-tailed portion 11, formed integrally therewith.

The dove-tailed portion 11 consists of 70 laminations which are clamped between the flanges 6 of the hub portion 1 (Fig. 2). The discs 4, constituting the hub portion 1, are assembled between a pair of pressure dies 12, provided with ring-shaped electrodes 13, and pressure is applied thereto to compress the fibrous sheets or laminations 11 until the web portions 7 of the discs 4 make contact. The ring electrodes 13 are energized with a suitable welding 80 current to weld the contacting web portions into an integral structure.

The web portion 7 may be provided with protuberances 15, which may be in the form of an annular projection or spot projections, as illustrated in Figs. 2 and 4. The projections provide heat and pressure-localizing contact portions, which become fused with the adjacent surface by welding. Instead of welding the hub members, they 90 may be united by rivets 17, Figs. 1 and 7, or in any other suitable manner.

The non-metallic rim 2 may be formed from a continuous strip 18, (Fig. 8), of fibrous material, such as fabric, which is 95 partially treated by a binding agent, as indicated by the shaded portion 9 and wound into a continuous helix of superposed layers to form a ring which is subsequently compressed and heated to consolidate the 100 treated portion, as above. In winding the strip 18 into a helix, it may be necessary to crimp or otherwise distort the material to compensate for the difference of the outer and inner circumferences of the ring 105 so formed. However, the surplus material of the untreated portion will be assembled between the flanges 6 of the hub member, as described above, to form a gear wheel.

Referring to Figs. 5, 6 and 7, the rim 2 110 may be united with the hubs 1 in various ways. For instance, in Fig. 5, the flanges 6 are provided with annular grooves 19, which are adapted to receive metal rings such as wires 20, which are forced into the 115 fibrous material 11 by pressure, to prevent any movement between the rim and the hub member. In Fig. 6, the projections 20', provided by the wires 20, (Fig. 5) may be an integral part of the flange 6. In Fig. 7, 120 the hub may comprise a solid web and rim portion having a single 21 and an offset portion 22, which is adapted to receive the flanged ring 23. The ring 23 may be secured to the hub by a plurality of rivets 17 or 125 by welding.

Referring to Fig. 4, the complete gear wheel is provided with a plurality of teeth 3, which are formed in the usual ways, as by cutting or generating. The teeth are 130

formed in the consolidated body portion extending beyond the flanges of the hub. The depth of the consolidated portion may vary from the top to the bottom of the gear teeth or to the top of the flanges or even below the flanges themselves.

Gear wheels formed in accordance with the above description of my invention are provided with a solid metal hub support 13 and a consolidated non-metallic working body portion having gear teeth, and having a relatively yielding intermediate portion therebetween. The advantages of this construction are as follows: The hub portion 15 may be formed of sheet metal punchings (castings), or forgings which are readily united by riveting or welding. The non-metallic rim is simple to form inasmuch as the excess material at the inner portion of 20 the rim is compressed between the flanges of the hub and the outer portion is a self-sustaining working body which requires no shrouding, thereby eliminating the possibility of metallic contact with the tooth of 25 the mating gear with which it is engaged. The non-treated fibrous portion between the working body portion and the supporting hub provides a yielding cushioning medium through which the torque of the gear wheel 30 is transmitted and further prevents splitting of the toothed portion.

It will be readily understood from the above description of my invention that gear wheels formed in accordance therewith are 35 silent in operation because of a non-treated intermediate portion which eliminates resonance and that the working body portion is resilient and yielding to sudden shock and impact and further process a wear resisting tooth portion which compares favorably 40 with the wearing qualities of soft steel and cast iron.

Although I have described a specific embodiment of my invention, it will be obvious 45 to those skilled in the art that various modifications may be made in the details and the method of construction without departing from the principles herein set forth. For instance, the hub portion may assume any 50 shape or form, and the method of fastening the hub members may be varied, inasmuch as any suitable mechanical interlocking means may be substituted for the rivets or the welded joints. The rim construction 55 may be varied in design to obtain any degree of resiliency in the tooth portion as by inserting untreated fibrous portions radially or axially in the consolidated body portion. Any suitable fibrous material, such as wood, 60 wood veneer, fabric, paper, asbestos, raw-hide, or vulcanized fiber, may be employed for the rim member, and any suitable binding agent, such as caesin, blood glue, and the like may be substituted for the phenolic condensation product. The successive steps of 65

the process or molding the rim and assembling it between the hub flanges may be reversed as the built-up ring may be compressed between the hub flanges prior to molding the outer body portion or the joining of the hub portions and the molding of the rim may be contemporaneous operations. The fibrous material may be treated by dipping after it is assembled to the hub or it may be treated by impregnating it 75 throughout but molding it only to the flange portion.

I claim as my invention:

1. A composite article comprising a hub portion and a non-metallic rim portion, said 80 rim portion being partially consolidated with a hardened binder.

2. A composite article comprising a hub portion and a partially consolidated non-metallic rim portion of varying density 85 mounted thereon and secured thereto.

3. A composite article comprising a metallic hub, and a non-metallic rim mounted thereon and secured thereto by parallel flanges of said hub, extending radially on 90 the respective side faces of said rim and engaging a portion thereof, said rim consisting of a non-metallic material having its outer body portion extending beyond said hub flanges of greater density than the remaining body portion.

4. A composite article comprising a metallic hub, and a non-metallic rim mounted thereon and secured thereto by parallel flanges of said hub, extending radially on 100 the respective side faces of said rim and engaging a portion thereof, said rim consisting of a non-metallic material having its outer body portion extending beyond said hub flanges of greater density than that portion between the said flanges.

5. A composite article comprising a metallic hub, and a non-metallic rim mounted thereon and secured thereto by parallel flanges of said hub, extending radially on the 110 respective side faces of said rim and engaging a portion thereof, said rim consisting of a non-metallic material having its outer body portion extending beyond said hub flanges consolidated with a hardened binder, 115 and having its remaining body portion untreated.

6. A composite article comprising a hub, and a non-metallic rim mounted thereon and secured thereto, said rim being consolidated with a hardened binder from its outer periphery to a predetermined depth extending radially inward and having its loose body portion compressed between a pair of flanges of said hub.

7. A composite article comprising a hub, and a non-metallic rim mounted thereon and secured thereto, said rim being consolidated with a hardened binder from its outer periphery to a predetermined depth extend- 120

- ing radially inward and having its loose body portion secured between a pair of flanges on said hub.
8. A composite article comprising a hub, 5 and a rim of fibrous material mounted thereon and secured thereto, said rim being consolidated with a phenolic condensation product from its outer periphery to a predetermined depth extending radially inward 10 and having its loose body portion secured between a pair of flanges of said hub.
9. A composite article comprising a hub, and a non-metallic rim mounted thereon and secured thereto, said rim comprising a 15 flat strip of fibrous material helically wound into a plurality of superposed convolutions edgewise on the periphery of said hub and secured thereon by a pair of flanges which are adapted to engage a portion of said rim, 20 the body portion extending radially outward from said flanges being consolidated with a hardened binder, and the remaining body portion of said fibrous material being free from a binding agent.
- 25 10. A composite article comprising a hub portion consisting of a pair of metal discs secured to form a unitary member, and a non-metallic rim mounted on said hub member said rim being partially consolidated 30 with a hardened binder.
11. A composite article comprising a hub portion consisting of a pair of metal discs secured to form a unitary member, a non-metallic rim secured between offset flanges 35 of said hub member having part of its body portion clamped therebetween and having the portion extending beyond said flanges of greater density than said clamped portion.
12. A composite article comprising a hub 40 portion consisting of a pair of metal discs secured to form a unitary member, a non-metallic rim secured between offset flanges of said hub member having part of its body portion compressed therebetween and having 45 the portion extending beyond said flanges of greater density than said clamped portion.
13. A composite article comprising a hub, a non-metallic fluted rim mounted thereon, 50 the fluted portion of said rim being of greater density than its remaining body portion.
14. A composite article comprising a hub, a non-metallic rim having a consolidated 55 fluted portion mounted on said hub and yielding means between the fluted portion of said rim and the said hub, said means consisting of a fibrous body portion comprising an integral part of said consolidated portion.
- 60 15. A composite article comprising a hub, a non-metallic rim having a fluted portion consolidated with a hardened binder mounted on said hub and yielding means between the fluted portion of said rim and the said 65 hub, said means consisting of a fibrous body portion comprising an integral part of said consolidated portion.
16. The method of making a composite article which comprises, forming a ring of fibrous material having only a portion of its body treated with a binder and consolidating said treated portion to form an integral mass. 70
17. The method of making a composite article which comprises forming a ring of fibrous material having only a part of its body portion treated with a binder and consolidating said treated portion to form an integral mass. 75
18. The method of making a composite article which comprises forming a ring of fibrous material having only a part of its body portion treated with a binder and consolidating said treated portion under the influence of heat and pressure to form an integral mass. 80
19. The method of making a composite article which comprises forming a ring of superposed layers of fibrous material being partially treated with a binder, and consolidating said treated portion under the influence of heat and pressure to form an integral mass. 85
20. The method of making a composite article which comprises forming a ring of superposed segments of fibrous material being partially treated with a binder, and consolidating said treated portion under the influence of heat and pressure to form an integral mass. 90
21. The method of making a composite article which comprises forming a ring of superposed layers of fibrous material having the laminations radially disposed with the center thereof partially treating said layers with a binding agent and consolidating said treated portion. 95
22. The method of making a composite article which comprises forming a ring of fibrous material by superposing a plurality of laminations having a partial treatment of a binding agent in alignment, subjecting the buildup laminations to heat and pressure to consolidate the treated portions, assembling the ring so formed between the flanges of a hub member and compressing the material therebetween, and simultaneously securing the hub members to form an integral structure. 100
23. The method of making a composite article which comprises forming a ring of superposed layers of fibrous sheet material having its outer body portion treated with a binder, consolidating the treated portion by the application of heat and pressure and clamping the untreated portion under pressure between the flanges of a hub. 110
24. The method of making a composite article which comprises forming a ring of superposed layers of fibrous sheet material 115
- 120
- 125
- 130

- having its outer body portion impregnated with a binder, consolidating the impregnated portion by the application of heat and pressure and clamping the untreated portion under pressure between the flanges of a hub. 5
25. The method of making a composite article which comprises forming a ring of superposed layers of fibrous sheet material having its outer body portion treated with 10 a phenolic condensation product, consolidating the treated portion by the application of heat and pressure and clamping the untreated portion under pressure between the flanges of a hub. 15
26. The method of making a composite article which comprises forming a ring of superposed layers of fabric having its outer body portion treated with a phenolic condensation product, consolidating the treated portion by the application of heat and pressure and clamping the untreated portion under pressure between the flanges of a hub. 20
27. The method of making a composite article which comprises forming a ring of 25 an endless strip of fibrous material having its outer body portion treated with the binder, consolidating the treated portion by the application of heat and pressure and clamping the untreated portion under pressure between the flanges of a hub. 30
28. The method of making a composite article which comprises forming a ring of superposed layers of fibrous sheet material having its outer body portion treated with a 35 binder, consolidating the treated portion by the application of heat and pressure, and securing the flanges to maintain the clamped ring portion under compression. 30
29. The method of making a composite 40 article which comprises forming a ring of superposed layers of fibrous sheet material having its outer body portion treated with a binder, consolidating the treated portion by the application of heat and pressure, 45 clamping the untreated portion under pressure between the offset flanges of a pair of metal discs and securing said discs to form an integral structure. 45
30. The method of making a composite article which comprises forming a ring of superposed layers of fibrous sheet material having its outer body portion treated with a binder, consolidating the treated portion by the application of heat and pressure, clamping the untreated portion under pressure between the offset flanges of a pair of metal discs and securing said discs by welding to form an integral structure. 50
31. The method of making a composite article which comprises forming a ring of superposed layers of fibrous sheet material having its outer body portion treated with a binder, consolidating the treated portion by the application of heat and pressure, clamping the untreated portion under pressure between the offset flanges of a pair of metal discs and securing said disc by riveting to form an integral structure. 55
32. The method of forming composite articles which comprises forming a ring of superposed layers of fibrous sheet material having its outer body portion treated with a binder, compressing and securing the untreated portion between the flanges of a metal hub and subsequently consolidating the treated portion by the application of heat and pressure. 60
33. The method of making a composite article which comprises superposing layers of fibrous sheet material having only parts 65 of their body portions treated with a binder and consolidating said treated portions to form an integral mass. 75
34. A composite gear wheel comprising a sheet-metal supporting member and a composite molded rim member mounted thereon, 80 said supporting member comprising a sheet-metal punching having a web portion, a hub portion and peripheral flange portions for engaging and supporting said molded rim member. 85
- In testimony whereof, I have hereunto subscribed my name this 13th day of March, 1925.

RANDAL E. TALLEY.
